US00D475699S

(12) **United States Design Patent** (10) Patent No.: **US D475,699 S**
 Thornton et al. (45) Date of Patent: ** Jun. 10, 2003

(54) **INSTRUMENT OR VOCAL MICROPHONE**
 (PG57)

(75) Inventors: **Brian Thornton**, Tinley Park, IL (US);
Curtis Leroy Cruver, IV, Elmhurst, IL (US)

(73) Assignee: **Shure Incorporated**, Evanston, IL (US)

(**) Term: **14 Years**

(21) Appl. No.: **29/153,727**

(22) Filed: **Jan. 11, 2002**

(51) LOC (7) Cl. **14-01**

(52) U.S. Cl. **D14/228**

(58) Field of Search D14/224, 225,
 D14/226, 227, 228, 229; 181/158, 242;
 381/157, 158, 181, 355, 356, 357, 358,
 359, 360, 369, 361

CLAIM

The ornamental design for a instrument or vocal microphone (PG57), as shown and described.

DESCRIPTION

FIG. 1 is a perspective view of the instrument or vocal microphone (PG57) design;
 FIG. 2 is a front view thereof;
 FIG. 3 is a top view thereof;
 FIG. 4 is a side view thereof;
 FIG. 5 is a rear view thereof; and,
 FIG. 6 is a bottom view thereof.
